UNITED STATES PATENT OFFICE.

LOUIS E. LADD, OF PROVIDENCE, RHODE ISLAND.

STUD.

1,132,662.

Specification of Letters Patent. Patented Mar. 23, 1915.

Application filed December 8, 1914. Serial No. 876,034.

To all whom it may concern:

Be it known that I, LOUIS E. LADD, a citizen of the United States, residing at Providence, in the county of Providence and State 5 of Rhode Island, have invented certain new and useful Improvements in Studs, of which the following is a specification.

My invention relates to pipe stem studs and particularly to that type wherein the 10 stud proper is adapted to be brought into temporary alinement with the shoe in order to facilitate insertion.

The essential objects of my invention are to increase the strength and facilitate the 15 manipulation of such structures, as well as to simplify and cheapen the construction of the same.

To the above ends essentially my invention consists in such parts and combinations 20 of parts as fall within the scope of the appended claims.

In the accompanying drawings which form a part of this specification, Figures 1 and 2 are side elevations of my stud in 25 closed and open positions respectively, Figs. 3 and 4, partial longitudinal central sections of the same shown in Figs. 1 and 2 respectively, Figs. 5 and 6, plan and side elevations respectively of the fixed member, and 30 Figs. 7 and 8, detail views of the slidable rod and the stud member respectively.

Like reference characters indicate like parts throughout the views.

In detail my stud comprises a cylindrical 35 tubular shoe or stem A provided with a point α on one end, and an inwardly directed shoulder or shoulders α' on the other formed at each side of a longitudinally extending guide plate B integral with the tube 40 A and provided with a longitudinal slot b opening into the tube. The outer end of the guide has a point b' . Slidably mounted in the tube A is a rod C of greater length than the tube provided with a shoulder c 45 on its outer end, against which bears the end of a helical spring D surrounding the rod, and whose opposite end abuts against the shoulder α' . A pivot pin E is mounted in or integral with a portion of the rod 50 which normally projects beyond the end of the tube and into the guide slot b . A stud post F has a bifurcated lower portion forming parallel ears f provided with openings f' to receive the pin E whereby the post 55 is pivotally connected with the rod. Inter-

mediate the ears the post is provided with a pointed cavity g . Upon the post is a head G, completing the post member.

The operation of the stud is similar to those of this type. Preparatory to insertion 60 the stud is moved from its normal position shown in Fig. 3 to the position indicated in Fig. 4, where the post F is in alinement with the tube A and the point b' registers in the cavity g . The pointed character of 65 the guide end and cavity tend to maintain the parts in alinement, and the increased pressure of the spring D on the rod increases this result. Thus the shoe and stud portions of the device are temporarily rigid, 70 and the stud may be easily inserted into a garment.

It will be noted that in seating and unseating the stud member relatively to the point b' no manipulation of auxiliary parts is 75 required. The integral character of the plate B relatively to the tube, and the protection that this guide plate affords to the rod moving in the slot b imparts strength and protection to the entire structure. The 80 location of the pivot member in the rod insures strength at the point of greatest strain.

What I claim is,—

1. In a stud, the combination of a tubular body, a guide plate integral with the tube 85 and provided with a longitudinal slot, a rod slidably mounted in the tube and extending into the slot, a pivot pin in the rod, a spring engaging the tube and rod, a post, ears upon the post engaging the pin and embracing 90 the plate, said post being provided with a cavity between the ears, and a head on the post.

2. In a stud, the combination of a tubular body, a guide plate integral with the tube 95 and provided with a longitudinal slot, and with a point upon its free end, a rod slidably mounted in the tube and slot, resilient means upon the rod for maintaining a portion of the rod within the tube, a post pivotally connected with the rod, a pointed cavity in the post adapted to receive the point upon the guide plate, and a head on the post. 100

In testimony whereof I have affixed my signature in presence of two witnesses.

LOUIS E. LADD.
